UNITED STATES PATENT OFFICE.

HENRY M. COLLESTER, OF GARDNER, MASSACHUSETTS.

DESIGN FOR CANE FABRIC.

SPECIFICATION forming part of Design No. 26,553, dated January 19, 1897.

Application filed December 11, 1896. Serial No. 615,410. Term of patent 7 years.

To all whom it may concern:

Be it known that I, HENRY M. COLLESTER, of Gardner, in the county of Worcester and State of Massachusetts, have invented and produced a new and original Design for Cane Fabric, of which the following is a specification.

Reference is to be had to the accompanying drawing, forming a part of this specification, which shows a piece of cane fabric with my design applied.

The leading feature of my design consists in the arrangement of the companion parallel stripes *a a* and the intersecting stripes *b*, each of a contrasting color from the body of the fabric, the stripe *c* arranged between the stripes *a a* and of a contrasting color from the said stripes and the body of the fabric and depressed centrally to show the body of the fabric in cross-shaped figures separated by the stripes *b*. The stripes *a* are depressed on their opposing margins to show the body of the fabric in the form of marginal checks.

f represents a piece of cane fabric bearing

my design, which consists of the companion parallel stripes *a a* and intersecting stripes *b* of a contrasting color from the body of the fabric. Between each pair of companion stripes *a a* is arranged the stripe *c* of a contrasting color from the body of the fabric and from the stripes *a* and *b*. The stripe *c* is depressed centrally to show the body of the fabric to form crosses separated by the stripes *b*. The stripes *a* are depressed upon their opposing margins to show the body of the fabric in the form of marginal checks.

I claim—

The design for cane fabric, as herein shown and described.

In testimony whereof I have signed my name to this specification, in the presence of two subscribing witnesses, this 30th day of November, A. D. 1896.

HENRY M. COLLESTER.
